UNITED STATES PATENT OFFICE.

AUGUST KLINZING, OF ST. CLOUD, WISCONSIN.

CARRIER.

No. 837,306.

Specification of Letters Patent.

Patented Dec. 4, 1906.

Application filed April 9, 1906. Serial No. 310,660.

To all whom it may concern:

Be it known that I, AUGUST KLINZING, residing in St. Cloud, in the county of Fond du Lac and State of Wisconsin, have invented 5 new and useful Improvements in Carriers, of which the following is a description, reference being had to the accompanying drawings, which are a part of this specification.

My invention has relation to improvements 10 in carriers.

The primary object of the invention is to provide a convenient and simple construction for carrying a load from the point of loading to a place of discharge, and it may be used to 15 great advantage for carrying manure or other substances from the interior of a barn or stable to a convenient point for dumping exterior of said barn or stable.

With the above primary object and other incidental objects in view the invention consists of the devices and parts or their equivalents, as hereinafter set forth.

In the accompanying drawings, Figure 1 is a side elevation of the device, parts being in 20 section and parts broken away. Fig. 2 is an end view of Fig. 1, the turn-table mechanism being in section; and Fig. 3 is a fragmentary detail view.

Referring to the drawings, the numerals 4 25 indicate two trolley-wheels mounted on short axles 5 5. The said axles may be supported in any suitable form of framework; but I prefer to provide for the purpose two housings 6 6, consisting of vertical members 30 having their upper portions bent over. The trolley-wheels are disposed between the walls formed by the main portions of the housings and the bent-over portions thereof and the axles are supported in said walls. The lower 35 ends of the main portions of the housings are connected by means of a transverse bar 7. Beneath the transverse bar is the upper member 8 of a turn-table, said member consisting 40 of a ring provided at its upper edge with inwardly-extending lugs 9, which are bolted to the transverse bar. The lower edge of the member 8 is outwardly turned to form an annular flange 10, and this annular flange 45 underlies an annular flange 11 at the upper edge of the lower member 12 of the turn-table, said lower member also being in the form of an annulus or ring. The lower member of the 50 turn-table is rigidly secured to the horizontal member 13 of an inverted-U-shaped suspending-frame. Each vertical portion of this suspending-frame consists of two straps 14 14.

The upper ends of these straps are bent inwardly and receive therebetween the opposite ends of the horizontal member 13 and are connected thereto by means of transverse 60 bolts 15 15.

The box or receptacle for containing the manure or other substance is indicated by the numeral 16, and this box or receptacle is pivotally suspended at its ends between the 65 depending vertical portions of the inverted-U-shaped suspending-frame. The pivotal connection is formed by securing blocks 17 17 between the straps 14 of each of said vertical members of the frame, and through these 70 blocks and through the ends of the box or receptacle are passed pivot-pins 18 18. The portions of the pivot-pins which pass through the ends of the box are threaded to receive nuts 19 19, located on the pins so as to be disposed on opposite sides of the ends of the box, and these nuts are adapted to be turned on the threads against said opposite sides of the box. By this provision the pivot-pins can be 75 tightened at any time.

Any suitable form of rail for the trolley-wheel to travel on may be provided, and in the embodiment of my invention illustrated in the accompanying drawings I have shown an ordinary trolley-wire 20, which is suitably 80 supported within the barn or stable and is carried out of said barn or stable to a conveniently located point for dumping, being also suitably supported exterior of the barn.

In view of the fact that the box or receptacle is pivotally or tiltably supported between the vertical members of the suspending-frame it is necessary that means should be provided for locking the box or receptacle in its normal position during the filling operation, and also during the time the carrier is traveling from within the barn to the exterior thereof, and in connection therewith suitable means for releasing the box or receptacle so that it may be tilted at the proper 90 time and its load thereby dumped. Of course hand-operated means for accomplishing this purpose could be employed; but I prefer to employ an automatically-operated means, one form of which is illustrated in the 95 accompanying drawings and which will now be described. Referring to this automatically-operated locking and unlocking mechanism, the numeral 21 indicates a link which is disposed centrally in the turn-table and extends loosely through an opening in the top member of the suspending-frame. The up- 100 105 110

per end of this link is provided with a grooved head, and fitting the groove are the arms of a fork 22, which extend at right angles from the lower end of a short rod 23, the upper end 5 of said short rod being also bent at right angles in a direction transverse of the length of the trolley-wire, as indicated by the numeral 24. To the lower end of the link 21 is pivoted a horizontal lever 25, fulcrumed to a lug 26, depending from the under side of the horizontal member 13 of the suspending-frame. The outer end of this lever in turn is 10 pivotally connected to a locking-dog 27, the said locking-dog at its lower end being provided with an inwardly-extending foot portion 28, which is adapted to ride over the curved upper edge of a rail 29, secured to and outstanding from one end of the box or receptacle and provided centrally with a notch 30. Fixedly secured to and depending from 15 a suitable point of the trolley-wire is a tappet 31, the lower edge of which being preferably conical, so as to present two oppositely-inclined surfaces. It will be apparent from 20 the description of the last-referred-to mechanism that when the foot 28 of the dog 27 is in engagement with the central notch 30 of the curved rail, as shown in Figs. 1 and 2, the box or receptacle 16 is locked against tilting. 25 Now if the carrier is caused to travel along the trolley-wire in a direction toward the tappet the bent end 24 of the rod 23 will be brought into contact with said tappet, and with the continued travel of the carrier the 30 incline of the conical lower edge of the tappet which is next to the approaching carrier will ride over the bent end 24 of rod 23, and thereby cause a down movement of said rod, and this rod in turn by reason of its connection to 35 the upper end of the link 21 will cause a downward movement of said link. The down movement of the link will have the effect of turning the lever 25 in a direction to elevate the outer end of said lever, and this necessarily lifts dog 27, and consequently raises the 40 foot 28 of said dog out of engagement with the notch 30 of the rail 29, the foot at this time resting on a point of the edge of the rail to one side of the notch. The box or receptacle is by the described action unlocked and 45 can be readily tilted by hand or otherwise to effect the dumping operation. After the contents of the box or receptacle are dumped the carrier is caused to travel back toward 50 its initial position, and whenever it is desired to again load the box or receptacle said box or receptacle is tilted back to upright position, when of course the foot 28 will automatically engage the notch 30 and lock the box in said 55 upright position.

In both the loading and unloading operations it is desirable that the box or receptacle be turnable in a horizontal plane, so as to place it in a most advantageous position for 60 being filled with material or for being

dumped. For instance, if the material with which the box is to be loaded is located adjacent to one of the ends of the box it will be exceedingly inconvenient to have to shovel the material over said end or to be compelled 70 to carry a shovelful of the material from the said position occupied by the material to a point where the shovelful can be thrown over the side of the box, and also in the case of unloading, unless provision is made for 75 turning the box or receptacle horizontally, the point at which the dumping is desired to take place may be inaccessible. It is for these reasons that I employ the turnable mechanism hereinbefore fully described. Some 80 means, however, should be provided to guard against the box or receptacle being turned at times when the turning is not desired, and in order to provide for this I employ a catch 32, pivoted at one end to the connecting-bar 7 85 and having its opposite ends bent downwardly in position to engage notches 33 in lugs 34, secured to diametrically opposite points of the annular flange 11 at the upper edge of the lower turn-table member 12. 90 The upper edges of these lugs are advisably beveled in opposite directions toward and to the central notches, so that when the parts are swung from a turned position back toward the normal position shown in the drawings the bent end of the catch 32 will ride on the incline and automatically engage the notch by gravity when the normal position is reached. A finger-piece 35 projects laterally from the catch 32 to provide a convenient 100 means for raising the catch out of engagement with the notch when it is desired to turn the box or receptacle.

As the trolleys have a tendency to "jump" the rail, I deem it advisable to guard against 105 this, and therefore provide guard-plates 36 36, one of said plates secured to and depending from the lower end of the turned-over portion of each housing 6 and extending a desired distance below the trolley-wire 20. 110 It is obvious that these guard-plates 36 form an effective means against the trolley-wheels disengaging entirely the wire, as the distance which the plates extend below the said wire is greater than the limited upward movement or jump to which trolley-wheels are 115 subject.

While I have in the accompanying drawings shown certain details of construction, yet I do not wish to be understood as limiting 120 myself in all instances specifically thereto, inasmuch as variations and modifications can be made without departing from the spirit and scope of the invention.

What I claim as my invention is—

1. In a carrier, the combination of a suspending-frame, a box or receptacle pivoted between the depending arms of said frame, a trolley-carrying frame, a trolley wire or rail on which the trolley-carrying frame is sus- 130

pended, an upper fifth-wheel member connected to the trolley-carrying frame and constructed in the form of a ring or annulus, a lower fifth-wheel member connected to the suspending-frame, and also constructed in the form of a ring or annulus, and in line with, and having a rotatable connection, with the upper fifth-wheel member, a locking-dog, a device carried by the box or receptacle which the locking-dog is adapted to releasably engage in order to hold the box or receptacle normally in upright position between the depending arms of the suspending-frame, a lever medially fulcrumed to the upper portion of the suspending-frame, and having its outer end pivotally connected to the upper end of the locking-dog, a vertically-movable link extending through the openings of the aligned annular fifth-wheel members, the lower end 20 of said link being connected to the inner end of the lever, and the upper end of said link provided with a grooved head, a rod having a forked lower end, the furcate members engaging the grooved head at the upper end of the link, and a fixed tappet, adapted, when the carrier is moved a certain distance, to contact with the upper end of the rod to thereby cause a down movement of the link, and consequent turning of the lever in a direction to cause an uplifting of the locking-dog and its disengagement from the device carried by the box or receptacle.

2. In a carrier, the combination of a suspending-frame, a box or receptacle carried by said frame, a lower fifth-wheel member secured to the upper portion of said suspending-frame, said fifth-wheel member being in the form of a ring or annulus having an inturned flange at its upper edge, a trolley-carrying

frame, a trolley-rail on which the trolley-carrying frame is suspended, an upper fifth-wheel member secured to the trolley-carrying frame and also of annular form but of less diameter than the lower fifth-wheel member, and provided at its lower edge with an 40 outturned flange adapted to engage under the inturned flange at the upper edge of the lower fifth-wheel member, a notched part carried on the inturned flange of the lower fifth-wheel member, and a dog comprising a 45 horizontal arm and a depending arm, said horizontal arm pivoted at its end to the trolley-carrying frame, and the depending arm adapted to releasably engage the notch of the notched part, and thereby hold the suspending-frame and its box or receptacle normally 50 against being rotated in a horizontal plane.

3. In a carrier, the combination of a suspending-frame, a box or receptacle carried by said frame, a lower fifth-wheel member secured to the upper portion of the suspending-frame, a trolley-carrying frame, an axle carried by said frame, a trolley on the axle, a trolley-rail on which the trolley travels, an upper fifth-wheel member secured to the trolley-frame and having rotatable connection with the lower fifth-wheel member, and a dog pivoted to the trolley-carrying member, and adapted to releasably engage a notch located therebelow and thereby hold said suspending-frame and its box or receptacle normally 60 against being rotated in a horizontal plane.

In testimony whereof I affix my signature in presence of two witnesses.

AUGUST KLINZING.
